JAW CRUSHER

Edgar B. Symons, Hollywood, Calif., assignor to
Nordberg Manufacturing Company, Milwaukee,
Wis., a corporation of Wisconsin

Application April 9, 1930, Serial No. 442,755

15 Claims. (CL 83—53)

My invention relates to an improvement in crushers, and particularly to an improvement in jaw crushers. A particular embodiment of my invention is a jaw crusher having one normally fixed jaw, and a normally moving jaw together with means for moving the moving jaw toward and away from the normally fixed jaw. One object of my invention is to obtain a product more uniform than that prevailingly delivered by jaw crushers now on the market. Another object is to increase the reduction obtained from such a jaw crusher. Another object is to reduce the production of fines in jaw crushers. Another object is the provision of means for relieving the opposed crushing members when tramp iron or uncrushable material passes therebetween. Another object is the provision of means for adjusting or setting the relative angle of the two jaws. Other objects will appear from time to time in the course of the specification and claims.

Certain matter pertaining to the lubrication features described and shown herein, but not claimed, are claimed in applicant's copending application Serial Number 470,277, filed July 24, 1930, now Patent No. 1,874,830.

I illustrate my invention more or less diagrammatically in the accompanying drawings, where-in—

- 30 Figure 1 is an end elevation;
- Figure 2 is a section on the line 2—2 of Figure 1;
- Figure 3 is a side elevation;
- Figure 4 is a section on the line 4—4 of Figure 35 2; and
- Figure 5 is a section on the line 5—5 of Figure 3.

Like parts are indicated by like symbols throughout the specification and drawings.

40 Referring to the drawings A generally indicates any suitable base or foundation or surface upon which the crushing machine may be mounted. The crushing machine frame generally indicated as A¹ includes any suitable bottom plate or flange portions A² which may be bolted, as by the bolts A³, to the foundations A. Preferably formed integrally with the plates or flanges A² are the upwardly extending frame members A⁴ between which is formed the tank 45 portion having the bottom wall A⁵, the side walls A⁶ A⁷, the top wall A⁸ and the transverse baffle or partition A⁹, depending from the top A⁸.

In the upper portion of each of the members A⁴ is a bearing or shaft engaging portion B to 50 which may be locked the opposed shaft engaging

portion B¹ as by the bolts B² and nuts B³. The shaft B⁴ is thereby mounted on and locked in relation to the frame members A⁴, extending transversely and horizontally between them. Surrounding said shaft B⁴ is a bearing bushing B⁵ of any suitable anti-frictional or wear taking material.

Surrounding the shaft B⁴, and adapted to rotate thereabout, is the hub C from which extends the jaw structure proper C¹. Preferably the bushing B⁵ is secured to and rotates with the hub C, about the outer surface of the shaft B⁴. As strengthening and reinforcement for the plate C¹ are provided a plurality of ribs C² which extend, as shown in Figures 1 and 2, from the hub C downwardly along and beneath the plate C¹. Transversely connecting the ribs C² is a transverse rib C⁴ having in it a plurality of enlargements in the form of perforated bosses C⁵. The ribs C² terminate at their lower or outer ends in a transverse rib C⁶ somewhat lower than the rib C⁴. A corresponding rib C⁷ extends across the bottom of the plate C¹, the ribs C⁶ and C⁷ being connected by longitudinal ribs C⁸, to form in effect a box structure, the purpose 25 of which will later appear. The ribs C² are provided with apertures C⁹ in enlargements or lugs C¹⁰ projecting from the ribs.

In order to actuate the jaw a driven shaft D is provided with an eccentric portion D¹. The shaft may be actuated as by the pulley or pulleys D², but it will be understood that any suitable drive may be employed. The shaft D may rotate for example in bearings D³ D³ formed in or associated with the opposite frame members A⁴. D⁴ indicates any suitable bearing bushings. Surrounding the eccentric portion D¹ of the shaft is a split sleeve formed with the boss D⁵ and D⁶ which may be locked together as by the bolts D⁷ and nuts D⁸. Within the sleeve 30 so formed, and surrounding the eccentric portion D¹ is any suitable bearing bushing or bushings D⁹, indicated in Figure 2 as split. Upwardly projecting from the member D⁶ is an arm D¹⁰ having inset in its outer surface a bearing block D¹¹. A corresponding bearing block D¹² is inset in the bottom of the jaw plate C¹, and a roller rod or bearing rod D¹³ is interposed between them, the blocks being channeled to receive it and conform to its cylindrical exterior. It will be understood that as the shaft D rotates the eccentric portion D¹ will impart to the arm D¹⁰ and thus to the jaw plate C¹ an oscillating or reciprocating movement. In order to maintain constant contact 35 40 45 50 55

with the roller D¹³ with the opposed blocks D¹¹ D¹², thus maintaining a firm and constant driving connection I provide the following.

Extending through the apertures C⁹ of the lugs C¹⁰ is a tube E the ends of which pass through eye-bolts E¹. The eye E² of each such bolt is held upon the end of the tube E, as by a washer I³ which may be fashioned in any suitable manner upon the tube E. I may for example employ a cotter pin I⁴. It will be understood that the ends of the tube E pass outwardly through the casting and that the eye-bolts E¹ are exterior to the members A⁴ of the casting. This aperture is indicated for example at I⁵ in Figure 3, the aperture being of sufficient size to permit a substantial movement of the tube E in relation to the frame. The aperture also permits inspection of interior parts. Each eye bolt E¹ passes through a lug I⁶ formed on the exterior of the frame member A⁴ and apertured as at I⁷ to permit the bolt to pass therethrough. An abutment I⁸, below said lug, is mounted upon each eye-bolt E¹, in the form of a stout washer which may be positioned as by the nuts I⁹ upon the screwthreaded end portion I¹⁰ of the eye-bolt. Compressed between the abutment or washer I⁸ and the lug I⁶ is indicated a spring I¹¹. It will be understood that the spring tends to draw the plate C¹ downwardly toward the shaft D, and thereby maintains a constant working and bearing connection between the roller D¹³ and the opposed blocks D¹¹ and D¹².

As a bearing or wear taking member to effect the actual crushing I may employ for example the face or crushing plate G. Its opposed edges are bevelled as at G¹ G². The lower bevelled edge G¹ is gripped by the overhanging portion G³ of the lower edge of the plate C¹. The upper edge is clamped, as by the wedge block G⁴. As shown in Figure 2 the plate C¹ is provided with a bevel, outwardly inclined surface G⁵ and, as will be seen from Figure 2, the wedge block G⁴ performs the double function of drawing down the upper edge of the plate G, and of thrusting the plate G longitudinally against the overhang G³ at the bottom of the plate C¹. The wedge blocks G⁴ may be drawn down as by the bolts G⁶, with their nuts G⁷, the bolts passing through the bosses C⁵. G⁸ indicates a wear taking plate adapted to protect the hub C from battering. It is removably mounted, as by the bolts G⁹ with the nuts G¹⁰. G¹¹ is a batter plate bolted as at G¹² to the lower edge of the plate C¹ below the lower edge of the wear plate G.

The jaw plate C¹ is also provided with side flanges G¹³, upwardly projecting, and generally aligned with the downwardly projecting flanges C⁸. The flanges C¹³ support and align the side plates G¹⁴. The plates G¹⁴ have the additional function of guiding the material passing between the crushing jaws, and preventing lateral escape from the crushing space. These plates G¹⁴, which are removable and renewable, move unitarily with the lower jaw structure.

It will be understood that, opposed to the movable lower jaw below described, is an upper jaw which is normally fixed. I provide means, however, for permitting movement of the upper jaw in case uncrushable material, such as tramp iron, passes through the crushing cavity. Referring for example to Figures 3 and 5, it will be seen that the side frame members A⁴ are provided at their upper edges with laterally expanded portions K in the form of flanges

laterally outwardly extending from the main web or plate A⁴. These flanges are provided with an outer downwardly turned portion K¹. The ends are supported for example by the inclined edged webs K², formed preferably integrally with the plate A⁴. An intermediate web or support K¹⁵ may also be employed. At two points, preferably adjacent the opposite edges of the portion K, it is recessed as at K³ to receive cylindrical projections K⁴ from the jaw plate supporting element generally indicated as L. These members K⁴ are in the form of cylinders with tapered expansions K⁵ at the outer ends, and corresponding tapered portions K⁶ at the inner ends. The apertures K³ are formed, as shown in Figure 5, to conform to the cylindrical conic portions K⁴ K⁷ and K⁸. The members K⁴ are normally held seated in the position in which they are shown by the securing caps or abutment plates K⁹ which overlie them and which are apertured or formed as at K¹⁰ to conform to them. These members K⁹ are downwardly thrust against the members K⁴ and the abutment webs or flanges K, for example by the employment of a plurality of bolts K¹¹. These bolts extend through the members K⁹ and the flange K, out of line with the members K⁴. Abutment members K¹⁰ are provided and between the members K¹⁰ and the lower surface of the flange K are compressed a plurality of springs K¹¹. K¹² indicate lock nuts for the tops of the bolts K⁹ and K¹³ indicate nuts or washers for the bottoms. It will thus be seen that the springs K¹¹ normally draw the members K⁹ downwardly toward the flanges K, whereby the jaw structure below described is normally held fixed in relation to the frame members A⁴. The jaw plate supporting structure generally indicated as L is associated with and preferably integral with the members K⁴, and overlies the moving jaw plate G. Each transversely aligned pair of members K⁴ is joined by an upper bridge structure or member L¹, and a lower bridge L², said bridges being connected by bosses L³, and by ribs or webs L⁴. The bosses L³ are apertured as at L⁵ for the passage therethrough of securing bolts L⁶ headed at their lower ends as at L⁷ and screwthreaded at their upper ends as at L⁸ to receive any suitable locking nuts L⁹. L¹⁰ is an abutment plate, through which the bolts pass, positioned above the upper bridge member L¹. Beneath it are a plurality of slightly yielding washers or layers of any suitable substance, for example fabric, indicated as L¹¹. This more or less yieldable material prevents snapping of the bolts due to the inertia of the upper jaw plate when the springs are compressed owing to the passage of tramp iron through the machine.

M generally indicates a carrier for the lower jaw plate proper M¹ which may be secured thereto for example by the overhanging portion M² and the wedge block M³ with its securing bolt M⁴. The member M is provided at each end with the transverse integral portion generally indicated as M⁵, each such portion having in the sides thereof a plurality of recesses M⁶ with penetrating slots M⁷, whereby the entire structure can be hooked upon the ends of the bolts L⁶, with the heads of such bolts L⁷ penetrating within the recesses M⁶. Between the upper face of each bridge member M⁵ and the lower face of each bridge member L² I may employ one or more washers or shims M⁸.

In order to maintain proper lubrication of the moving parts and to prevent the access of dust

to moving parts I provide the following system. Projecting upwardly about the connection D^{10} between the eccentric D^1 and the lower jaw structure C^1 I provide a surrounding housing structure generally indicated as O . This housing O is bolted as at O^1 to the oil container which includes the walls A^5 , A^6 , A^7 , A^8 and projects upwardly about the member D^{10} . It terminates in two concentric and somewhat arcuate walls O^2 O^3 opposed to washers or wiping members O^4 O^5 on the flanges C^6 and C^7 respectively of the plate support or jaw C^1 . It will be understood that the form of the opposed parts is such that as the jaw oscillates about its center of rotation the wiping members contact the exterior of the walls or members O^2 O^3 , preventing any access of dust to the closed housing thus formed. O^6 indicates a baffle adapted further to direct what slight dust does penetrate the housing away from the bearing roller D^{13} . It will be understood that the packing or wiping means O^4 O^5 are continued as at O^7 along the flanges or walls C^8 which connect the flanges C^6 C^7 . This structure will be clear from Figure 4.

I may provide any suitable oil circulating means for delivering oil from the oil housing to the bearings. I indicate for example a gear P upon the shaft D which gear meshes with and drives a pinion P^1 . The shaft P^2 , associated with the pinion, may drive any suitable pump mounted for example in the pump housing P^3 and not herein shown in detail. P^4 indicates an oil delivery pipe extending from the pump housing, along which the pump is adapted to direct a flow of oil. P^5 indicates an oil pipe extending from the oil reservoir to the pump, through which oil is drawn for delivery along the pipe P^4 . P^4 communicates with an oil duct P^6 which extends to the packing gland P^7 and communicates with an axial passage P^8 in the shaft D . An outlet P^9 for the said duct P^8 is adapted to deliver oil to the bearing surface of the eccentric D^1 . The oil may escape along the bushing D^9 and is delivered thereby to the bearings D^4 which are thus lubricated by the same oil streams or oil delivery. P^{10} indicates an oil delivery pipe extending to the packing gland P^{11} and therethrough to the axial or longitudinal passage P^{12} in the shaft B^4 . P^{13} indicate oil outlet ducts through the bearing surface of said shaft. They extend for example to the groove P^{14} in the bushing B^5 . P^{15} indicate return oil ducts whereby the oil drains back to a point adjacent the roller D^{13} which is thereby lubricated. The oil drips back into the reservoir. The baffle O^6 serves to prevent the drip or delivery of oil to the wiping member O^5 . P^{16} indicate oil return ducts from the oil collecting housings or members P^{17} , in one of which the pump drive is positioned as shown in Figure 1. Thereby all the oil delivered to the bearings D^4 is returned to the oil reservoir. P^{18} indicates an oil inlet pipe, having the cap P^{19} , whereby any desired quantity of oil may be delivered to the oil reservoir.

It will be observed that the oscillation or movement of the lower jaw structure progressively increases and diminishes the volume of air within the oil reservoir, owing to the fact that the cavity of the oil reservoir opens to the lower face of the plate C^1 . As the jaw rises there is a tendency to suck air into the oil housing and as the jaw falls there is a tendency to expel air. In order to prevent admission of dust by such air flow I provide an air inlet shown

for example in Figure 2 as follows. Q indicates the main air inlet passage closed by a perforated plate Q^1 . The perforations Q^2 are masked by a flexible diaphragm Q^3 , which permits movement of air downwardly through the apertures, but resists movement of air upwardly through the apertures, being flattened against the plate Q^1 by any upwardly exerted air pressure. Q^4 indicates a passage in communication with the top of the plate Q^1 . It is surrounded by a generally rectangular housing Q^5 with a perforated bottom Q^6 and any suitable dust retaining filling Q^7 , for example of fiber. Q^8 indicates a closed cover which, however, may be removed, as by loosening of the wing nuts Q^9 mounted on the pivoted eye-bolts Q^{10} . The result is the admission of dust-free air into the oil housing, through the aperture Q , associated with means for preventing retrograde movement of air upwardly through the aperture Q . It will be understood from this structure that as the jaw plate C^1 rises, air is drawn through the aperture Q . As the jaw falls air is forced downwardly around the packings O^4 O^5 O^7 , blowing away the dust, or preventing the inward movement of dust or dust filled air into the oil housing.

It will be realized that although I have described and shown a practical and operative device, nevertheless many changes may be made in the size, shape, number and disposition of parts without departing from the spirit of my invention. I therefore wish my description and drawings to be taken as in a broad sense illustrative and diagrammatic rather than as limiting me to my specific showing. In particular it will be understood that I do not wish to be limited, except so far as I limit myself in my claims, to any particular shape or profile or angle of crushing jaw or plate, as I may vary them considerably without destroying the characteristic action of the crusher.

The use and operation of my invention are as follows:

I employ a jaw crusher having preferably an inclined, lower jaw, and an upper jaw overhanging or overlying a substantial proportion of the area of the lower jaw. In the particular form of my device herein shown the lower jaw C^1 is pivoted adjacent or above the upper edge of its effective crushing area, and is oscillated or rotated, through a rather substantial arc, about its pivot, in such fashion that the travel or throw of the crushing plate G increases progressively from top to bottom. The driving connection is made from the lower portion of the crushing jaw, whereby the eccentric D^1 by its rotation oscillates or pivots the jaw C^1 , giving the plate G its characteristic crushing movement. The upper or overhanging jaw M , with the crushing plate M^1 is normally fixed upon the frame of the crusher. However, I provide a yielding connection between the upper jaw structure and the frame, whereby it may give in response to the passage of uncrushable material through the crushing machine. This obviates or greatly reduces the probability of stoppage or breakage. As the abnormal stress may occur at a variety of points along the plate M^1 , I provide a double tilting connection, whereby either the top or the bottom of the jaw may recede from the opposed jaw. Assume that a large mass of uncrushable material drops between the opposed crushing plates and engages the plate M^1 adjacent its upper edge, the plate

will then tilt about the lower pair of members K⁴, the upper edge of the plate M¹ tilting away from the upper part of the plate G. On the other hand, if the smaller uncrushable mass or member is wedged between the opposed crushing plates adjacent their lower edges, the jaw M may tilt about the upper pair of members K⁴. It is possible but not likely that an uncrushable mass may engage the central portion 10 of the jaw M and cause both ends to lift at once. In any case such a lifting movement would be so slight that upon its relief the springs K¹¹ would draw the member K⁸ back into position and there would be no permanent displacement of the members K⁴.

15 A characteristic method of operation of the present device is the employment of a more or less restricted feed, whereby a relatively sparse flow of the material to be crushed is delivered 20 to the upper portion of the crushing zone defined by the opposed plates G and M¹. When the machine is set up as shown in the drawings, and the drive shaft D is rotated, the eccentric D¹ rotates the lower jaw toward and away from 25 the upper jaw. The material to be crushed is fed in from above, falling freely under gravity into the crushing space between the opposed plates. As the lower jaw rotates or oscillates, material will be wedged or pinched between it 30 and the overhanging upper jaw. As soon as the lower jaw begins to recede from the upper jaw, each particle will commence to fall freely away from the upper jaw, the distance of its fall depending on the relation between the acceleration 35 due to gravity, the rate and length of movement of the jaw, the angle of the jaw, and the size of the particle. Since the upper jaw overhangs the lower, the dropping action of the material away from the crushing surface of the upper jaw 40 is obtained by withdrawing the lower jaw with sufficient rapidity and through an excursion of sufficient length downwardly and slightly laterally away from the effective crushing surface of the upper jaw. Therefore, after each crushing 45 impact the lower jaw is moved through an excursion of such length and at such a rate that it recedes from the upper jaw faster than the material can drop. The particles will fall generally vertically downwardly from the upper 50 jaw, after the lower jaw has been withdrawn, until they again strike the lower jaw. They will then move downwardly along the face of the lower jaw until the lower jaw returns again near enough to the upper jaw to nip the particles between the two jaws. When the lower 55 jaw reaches a point at which the distance between its surface and that of the upper jaw is equal to the diameter of the particles between the two jaws, then the downward movement of the particles ceases, and they are again crushed.

60 This alternation of vertical drop and crushing conveying movement continues until the particles being crushed have escaped from the crushing zone, and pass downwardly across the lower edge of the lower plate G, and over the guard or deflector G¹¹.

The action to which the articles being crushed is subjected may be divided into three parts. First, there is a free drop by gravity, which may 70 take place when the material is initially fed to the crushing zone, and which repeated after each crushing impact. Second, there is a supporting engagement between the lower jaw and the particles, after they have dropped so far as 75 to engage the lower jaw, but are not yet actual-

ly nipped between both jaws. Finally, there is the actual crushing impact, which begins on the up-stroke of the lower jaw, when the distance between the two jaws is no greater than the diameter of the particles being crushed. The crushing nip continues and effects the desired reduction, after which case the next following free drop under the influence of gravity.

Assuming a restricted feed, the initial drop, the sliding movement down the lower jaw, and the crushing impact against the upper jaw is effected with a crushing zone relatively sparsely filled with material. In order to obtain a positive sizing for the particles crushed, I provide a zone of parallelism X at the lower edges of 15 the opposed jaws or plates, in which zone the opposed faces of the plates are parallel at their point of closest approach. The length of the zone of parallelism is governed by two main factors: first, the speed imparted to the material by gravity, gravity being a constant force, and second, the interval of time between the crushing impacts, during which the material is permitted to drop as it is released by the increasing distance between the opposed jaws, and 20 during which it slides along or moves across the lower jaw prior to the crushing nip. The interval of time is governed by the speed of operation of the machine. The length of the zone of parallelism must be such that all the material passing therethrough will remain in the zone so long as to be caught at least once between the two jaws at their moment of closest 25 approach.

The maximum distance between the opposed 30 jaws is far greater than the ultimate size of the material being crushed.

In any crushing process the production of fines or dust is inevitable, but I reduce such degradation to a minimum, as I crush with a sparsely 35 filled crushing zone, and therefore with a minimum of crushing or grinding contact between particles. As the particles drop from the overhanging upper jaw to the lower jaw, they tend to spread out upon the surface of the lower jaw 40 and to slide or roll or skip freely downwardly thereacross. Thus when the material is crushed the particles tend not to be superposed upon each other and are not compacted but are freely spread or scattered in the crushing zone. The 45 larger particles project farther from the surface of the lower jaw than the smaller, and are crushed first. Particles which have for any reason been crushed at the preceding crushing impact to a size less than the governing minimum 50 distance between the two jaws at the next impact, are not crushed at all. The total throw of the lower jaw, stated in terms of its function or effect, is divided into a conveying excursion, during the time when the material is not nipped, 55 and a crushing excursion, which continues from the beginning of the crushing nip to the termination of the crushing nip or effect of any particular excursion of the jaw. The actual crushing excursion is in general substantially smaller 60 than the conveying excursion, and furthermore decreases progressively from top to bottom of the crushing zone. This is so since the material is successively reduced to smaller and smaller size, while the actual throw of the lower jaw increases 65 progressively from top to bottom. For example, in fine reduction, if the movement at the lower edge of the jaw were, say, 2½ inches, the actual crushing excursion might be not over ¼ of an 70 inch in length.

In connection with maintaining the feed of material through the crushing zone, and in order to prevent the wedging of small particles about the edges of the jaws I have formed the lower 5 jaw with upward side extensions G¹³ which support the cheek plates G¹⁴. These cheek plates are preferably removable and replaceable, and may be of any suitable material, for example manganese. Assume that material is caught between 10 the upper jaw plate M¹ and the cheek plate G¹⁴, when the lower jaw drops, the cheek plate moves down, moving with the lower jaw, and tends to pull the caught material downwardly, and to free it from the edge of the jaw plate 15 M¹. As the opening between M¹ and G increases, this material can fall laterally into this increasing open space, and falls back into the crushing zone. At every stroke of the lower jaw the cheek plate frees the trapped material, and tends to 20 feed it back into the crushing zone. This is particularly important in fine reduction, to prevent the trickling of oversize material downwardly along the edges of the jaw plates. This would be possible where the closest approach of 25 the jaw plates is less than the interval between the edges of the jaw plates and the cheek plates.

I claim:

1. In a jaw crusher, a normally fixed jaw and a moving jaw opposed thereto, the moving jaw 30 being oscillatable about a normally fixed pivot through a rectilinearly defined path and actuating means for said moving jaw including an eccentric link and a direct driving connection between said eccentric link and said jaw, a housing about said eccentric link and wiping connections 35 between the edges of said housing and the jaw.

2. In a jaw crusher, a frame including up-standing frame elements, a movable jaw pivoted 40 to said frame elements adjacent its upper edge, and a normally fixed jaw tiltably mounted upon said frame elements, and yielding means for normally maintaining it in fixed position, said means being adapted to permit it to tilt in response to a predetermined excess pressure within 45 the crushing zone between the two jaws, including clamping members associated with said frame elements, and yielding means for drawing said clamping members against said frame elements, which include guiding members associated with said clamping members and penetrating said frame elements, spring abutments upon said guiding members and springs compressed between said abutments and frame elements, the normally fixed jaw including portions interposed between said frame elements and said clamping members.

3. In a jaw crusher, a normally fixed jaw and a moving jaw opposed thereto, and actuating 60 means for said moving jaw including an eccentric member, and a direct driving connection between the eccentric member and the jaw, a housing about the eccentric member, wiping connections between the edges of the housing and the jaw, and air inlet and outlet means for said housing, said jaw being adapted, in response to its pulsating movement, to draw air into and to 65 expel air from said housing.

4. The structure of claim 3 which includes the 70 provision of means for expelling air from the housing past said wiping connections.

5. The structure of claim 3 which includes the 75 provision of means for expelling air from the housing past the wiping connections, the air inlet means being effective to admit air to the

housing at a point more or less distant from the wiping connections.

6. The structure of claim 3 which includes the provision of means for expelling air from the housing past the wiping connections, the wiping connections being adapted to prevent the passage of air inwardly therethrough into the housing.

7. The structure of claim 3 which includes the provision of air cleaning means adapted to admit cleaned air into the housing.

8. In a jaw crusher, a normally fixed jaw and a moving jaw opposed thereto, a frame element upon which said normally fixed jaw is mounted, a tilting connection intermediate said frame element and said jaw and yielding means adapted to hold said jaw normally in fixed position and adapted to permit it to tilt in relation to said frame element in response to predetermined excess stresses, said tilting connection including trunnions associated with the jaw, and arcuate bearing members associated with the frame and adapted to receive the trunnions, the yielding means being adapted to hold said trunnions normally seated against said bearing members, one such tilting member being provided adjacent the top and one adjacent the bottom of the jaw.

9. In a jaw crusher, a base, a frame upstanding from said base, a movable jaw pivoted about a normally fixed pivot adjacent the upper portion of said frame, and means for reciprocatingly rotating it about said pivot through a predetermined arc, an opposed jaw normally fixed in relation to said frame, said normally fixed jaw overlying said movable jaw throughout a substantial proportion of its area, and yielding means for normally holding the opposed jaw

fixed in relation to said frame, said means being yieldable to permit a recession of the normally fixed jaw from the movable jaw in response to predetermined pressures, tilting connections being interposed between the normally fixed jaw on the frame adjacent the upper and lower portions of the jaw, adapted to permit the jaw to tilt in relation to said frame selectively about the axes of either of said tilting connections.

10. In a jaw crusher, a normally fixed jaw and a moving jaw opposed thereto, a frame element upon which said normally fixed jaw is mounted, a tilting connection intermediate said frame element and said jaw and yielding means adapted to hold said jaw normally in fixed position and adapted to permit it to tilt in relation to said frame element in response to predetermined excess stresses, said tilting connection including trunnions associated with the jaw, arcuate bearing members associated with the frame and adapted to receive said trunnions, and yielding means for holding said trunnions normally seated against said bearing members.

11. In a jaw crusher, a base therefor, a normally fixed jaw and a moving jaw opposed thereto, driving means for said moving jaw, a housing for said driving means in said base, said driving means being located within said housing, said housing being adapted to contain a supply of oil, means for circulating said oil to the various bearings of the jaw crusher, including a pump and means for actuating it, said housing being in part closed by the moving jaw itself, an overlapping connection between housing and jaw, driving means extending between and being surrounded by said overlapping connection, and means for admitting air into and

expelling air from the housing in response to the movement of the jaw.

12. In a jaw crusher, a base therefor, a normally fixed jaw and a moving jaw opposed thereto, driving means for said moving jaw, a housing for said driving means in said base, said driving means being located within said housing, said housing being adapted to contain a supply of oil, means for circulating said oil to the various bearings of the jaw crusher, including a pump and means for actuating it, said housing being in part closed by the moving jaw itself, an overlapping connection between housing and jaw, driving means extending between and being surrounded by said overlapping connection, and means for admitting air into and expelling air from the housing in response to the movement of the jaw, and means associated with said air admitting means for cleaning the air admitted to the housing.

13. In a jaw crusher, a frame including upstanding frame elements, a movable jaw and a normally fixed jaw tiltably mounted upon said frame elements, and yielding means for normally maintaining it in fixed position, said means being adapted to permit it to tilt in response to a predetermined excess pressure within the crushing zone between the two jaws, including clamping members associated with said frame elements, and yielding means for drawing said clamping members against said frame elements, which include guiding members associated with said clamping members and penetrating said frame elements, spring abutments upon said guiding members and springs compressed between said abutments and frame elements, the normally fixed jaw including portions interposed between said frame elements and said clamping members.

14. In a jaw crusher, a frame including upstanding frame elements, a movable jaw mounted within said upstanding elements and means for imparting to it oscillation in a rectilinearly bounded path, a normally fixed jaw movably

mounted in relation to said frame elements and means for normally holding it in said fixed position, including abutments on said frame elements positioned at opposite sides of the path of movement of the movable jaw, yoke means extending to the rear of the jaw provided with laterally extending projections, said projections bridging said abutments, and means for urging said yoke means toward said abutment means, including cap members engaging said projections, and a plurality of springs positioned along each side of said frame exteriorly of the path of movement of the movable jaw, at opposite sides thereof, spring abutments on said frame, movable spring abutments positioned adjacent said frame elements, said springs being compressed between said abutments, and tension members connecting said movable abutments with said cap members.

15. In a jaw crusher, a frame including upstanding frame elements, a movable jaw mounted within said upstanding elements and means for imparting to it oscillation in a rectilinearly bounded path, a normally fixed jaw movably mounted in relation to said frame elements and means for normally holding it in said fixed position, including abutments on said frame elements positioned at opposite sides of the path of movement of the movable jaw, yoke means extending to the rear of the jaw provided with laterally extending projections, said projections bridging said abutments, and means for urging said yoke means toward said abutment means, including cap members engaging said projections, and a plurality of springs positioned along each side of said frame exteriorly of the path of movement of the movable jaw, at opposite sides thereof, spring abutments on said frame, movable spring abutments positioned adjacent and exterior to said frame elements, said springs being compressed between said abutments, and tension members connecting said movable abutments with said cap members.

EDGAR B. SYMONS.
